UNITED STATES PATENT OFFICE.

FRANK V. DOLDER, OF EARLVILLE, ILLINOIS.

APPARATUS FOR HOLDING MOTORS.

1,127,969.

Specification of Letters Patent.

Patented Feb. 9, 1915.

Application filed October 31, 1913. Serial No. 798,510.

To all whom it may concern:

Be it known that I, FRANK V. DOLDER, a citizen of the United States, residing at Earlville, in the county of La Salle and State of Illinois, have invented certain new and useful Improvements in Apparatus for Holding Motors; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in apparatus for holding motors while being overhauled and forming a convenient stand which is adjustable and so arranged as to enable the workman to have convenient access to the same in overhauling the motor.

The invention comprises various details of construction and combinations and arrangements of parts which will be herein-after fully described, shown in the accompanying drawings and then specifically defined in the appended claim.

I illustrate my invention in the accompanying drawings, in which:

Figure 1 is a perspective view of a stand for holding motors made in accordance with my invention, and Fig. 2 is an enlarged detail view showing the adjustment of the frame.

Reference now being had to the details of the drawings by letter, A, A designate standards connected to the base strips B which are suitably braced as at C and each of said standards has a boxing D in which the

spindles E of the racks are journaled. One of said spindles is extended and has a worm wheel F fixed thereto which is in mesh with the worm shaft H to which a handle I is fastened, forming a convenient means for turning the rack. The rack comprises two end pieces K which are parallel to each other and which are longitudinally slotted as at L, and two side bars, designated respectively by letters O, O, and each of which is provided with a laterally extending and longitudinally adjustable angle plate R which is held in an adjusted position within the slot through the medium of set screws S. It will be noted that each of said bars O has an offset O' provided as a convenience to receive the fly wheel of the engine.

By the provision of a stand made in accordance with my invention, it will be noted that the same may be adjusted to different sized motors and, by revolving the rack, the motor may be brought to different positions for convenience of workmen in overhauling the same.

What I claim to be new is:

A stand for holding motors while being overhauled, etc., comprising standards, slotted angle bars, pintles fastened to said bars and journaled in suitable bearings upon said standards, bars having offset portions and each provided with an angled projection movable within said slots, and means for holding the projections upon said offset bars in different adjusted positions.

In testimony whereof I hereunto affix my signature in presence of two witnesses.

FRANK V. DOLDER.

Witnesses:

G. H. WILEY,
EDNA ALBERT.
